UNITED STATES PATENT OFFICE.

ROBERT R. DEBACHER, OF HOBOKEN, NEW JERSEY.

DESIGN FOR A FRAME FOR BRUSHES, MIRRORS, OR SIMILAR ARTICLES.

SPECIFICATION forming part of Design No. 37,282, dated January 3, 1905.

Application filed November 14, 1904. Serial No. 232,745. Term of patent 14 years.

To all whom it may concern:

Be it known that I, ROBERT R. DEBACHER, a citizen of the United States, and a resident of Hoboken, in the county of Hudson and State of New Jersey, have invented a new, original, and ornamental Design for a Frame for Brushes, Mirrors, or Similar Articles, of which the following is a specification.

In the accompanying drawings, Figure 1 is a front view embodying my new, original, and ornamental design for a frame for brushes,

mirrors, or similar articles; and Fig. 2 is a side view.

What I claim is—

The ornamental design for a frame for 15 brushes, mirrors, or similar articles substantially as shown.

ROBERT R. DEBACHER.
